UNITED STATES PATENT OFFICE.

JAMES W. PROVARD, OF NOGALES, ARIZONA.

AUTOMATIC ADVERTISING DEVICE FOR STREET-CARS.

1,129,518.

Specification of Letters Patent. Patented Feb. 23, 1915.

Application filed March 23, 1914. Serial No. 826,627.

To all whom it may concern:

Be it known that I, JAMES W. PROVARD, a citizen of the United States, residing at Nogales, in the county of Pima and State of Arizona, have invented certain new and useful Improvements in Automatic Advertising Devices for Street-Cars, of which the following is a specification.

This invention relates to automatic advertising devices for street cars, and has for its object the production of automatic means for displaying advertisements one after another or several together, and color screens having special construction, arrangement, and mode of operation resulting from the particular structure disclosed, whereby it is believed the attention of the passengers in the car will be attracted to the advertisements, to the subsequent advantage of the advertiser. In street car advertising or the like, the stationary cards customarily arranged over the windows in the interior of the car, are now so commonly used, and for such a long time that the average person who has repeatedly seen such advertisements in his or her daily travel in the street cars is not attracted by them, however pretty or clever the cards may be. It is likewise the fact that an ordinary moving web or band carrying the cards or printed announcements fails of the effect intended for the like reason of commonplace experience.

It is an object of this invention not only to change the advertisements, but to change their color, and, as nearly as practicable, to cause each advertisement upon each of its successive appearances in the sight opening to seem to be differently colored. This object is attained by employing revolving colored screens of transparent material, that turn at different speeds and in different directions, both the speeds and directions of the screens being variable by reason of the interchangeable parts set forth.

Of the accompanying drawings wherein like parts are designated by like letters, Figure 1 represents the side of a street car provided with this invention. A portion of the side of the car is cut away to permit the various devices to be seen. Fig. 2 is a fragmentary view showing a cross-section of one of the screens and the method of supporting the end of the screen in its revoluble holder. Fig. 3 is a cross-section of the street car upon the line $x-x$ of Fig. 1 showing the face of the band carrying the advertise-

ments, and the relative positions and arrangement of the other parts. In Fig. 2 the scale of drawing has been somewhat increased to better the illustration.

Considering the drawings, a street car A has an axle a , about which passes a belt B in contact with a belt tightener b , and extending around the large pulley C on the transverse shaft c . A small pulley D, also on the transverse shaft c , is connected by the belt d with a large pulley E on the second transverse shaft e . A small pulley F, also on the second transverse shaft e , is connected by the belt f with the large pulley G on a third transverse shaft g . The intention in using the large and small pulleys belted together as illustrated is to introduce means for retarding the speed and compelling the parts carrying the advertisements to move somewhat slowly, as compared with the velocity at which the axle a revolves.

On the transverse shaft g is a small pulley H, and a belt J connects the small pulley H with the small pulley j arranged at a higher point as shown. The pulley j serves to transmit rotary movement to the transparent flat screens K, L, M, N, O, and the screens are arranged to operate in a sight opening, usually framed, in the end wall of the car and designated by the letter P. Each screen consists of a thin piece of colored glass, or, there may be more than one piece, such as the additional screen m revolving with the screen M. The screens are of different colors and differ in width. The screens make complete revolutions continuously. Each screen has a holder such as the holder k illustrated in Fig. 2 for the screen K, and the small pulley j is attached to the trunnion of the holder k . The screen holders are all precisely alike excepting as to the diameters of the circular portions thereof. Each screen has a holder at each of its ends, and the trunnions of the holders are all of the same size. The description of one of the holders will, therefore, answer for them all. Considering Fig. 2, it will be noted that the screen K is held between the diametrical ribs 1 and 2 of the circular portion of the holder k . It is preferred to cement the end of the screen to the ribs by means of rubber cement to prevent possible rattling as the car moves. The trunnion 3 of the holder k is journaled in a bearing 4 adjustable up and down on a vertical rod 5, and may be

secured at any point thereon by a setscrew 6. The other holders are likewise provided with the vertically adjustable bearings shown and all of the same size and construction as the bearing 4. As the bearings of the screens are all movable, it is believed to be clear that the bearings of the screens L, M, N, and O may be raised slightly, thereby separating the screens from the 10 driven screen K, and stopping their revolutions. That is to say, as the bearings of the revoluble screens are adjustable, the screens may be separated and certain of the screens may be kept stationary while others revolve. 15 It will be noted that the circular portion of the holder k, as best shown in Fig. 1, as well as the circular portions of all the other holders, is provided with leather or rubber peripheral coverings such as the facing 7 20 on holder k. These circular portions of the holders are, in fact, friction wheels and are all arranged in contact, in order that the rotation of the holder k by the pulley j will be communicated to all the holders and 25 screens. The reason for making the bearings of the holders adjustable is to render the screens interchangeable. So long as the circular portions of the holders are in contact, the screens may be arranged in any 30 order. Furthermore, by reason of the construction explained, the screens are turned at different speeds and in different directions, thus varying the color and effect of the screens through which the light must be 35 transmitted to the eyes of the observer. It will be understood that the screens are thin and very transparent in order that the advertisements may be easily read through them. It is the peculiar action of the 40 screens, sometimes coming together edge-wise, sometimes inclined, and sometimes horizontal flatwise, that attracts the attention of the passengers to the advertisements. Again considering Fig. 1 and Fig. 45 3, it will be seen that there is a second pulley h on the transverse shaft g, and it is the pulley h which transmits the movement of the shaft g to the band Q, by means of the belt q. The band Q, which is constructed to 50 carry advertising matter, is supported at the top and bottom upon the rollers R and S, and the belt Q encircles the roller S as usually arranged. The band Q is further directed in a desired vertical plane by means 55 of guide rollers r and s. The advertisements T are presented toward the interior of the car, and, in daylight, they are amply illuminated from the outside by way of the car window t and the sight opening P. At 60 night, the electric light globes U furnish artificial illumination, and the globes U are arranged between the screens and the band Q. It may be occasionally necessary to rotate 65 the various parts and move the band Q when the car is at a standstill. To that end there

is provided the removable handcrank V upon the transverse shaft 3, as shown in Fig. 3.

The operation of this invention is thought to be now clear from the drawings and the foregoing. The advertisements are slowly moved either up or down past the sight opening P, and they become apparently of various colors by reason of the screens, the screens at the same time giving the effect 75 of unique and unaccustomed movement and serving to attract the eyes.

Having now described this invention and explained the mode of its operation, what I claim is:—

1. In an advertising device, the combination with a movable member constructed to carry advertising matter, of means for actuating the said member, transparent colored screens arranged in front of the said member, each screen being revoluble, the axes of all the screens being parallel one to another, and means for continuously revolving the said screens upon their axes. 85

2. In an advertising device, the combination with a movable member constructed to carry advertising matter, of means for actuating the said member, transparent colored screens arranged in front of the said member, each screen being revoluble and provided with a friction wheel, the friction wheels of the said screens being arranged in contact with each other, and means for revolving one of the screens continuously on its axis thereby revolving the remaining 100 screens. 95

3. In an advertising device, the combination with a movable member constructed to carry advertising matter, of means for actuating the said member, transparent colored 105 screens arranged in front of the said member, each screen being revoluble, the axes of all the screens being parallel one to another, and means for continuously revolving the said screens upon their axes in different periods of time. 110

4. In an advertising device, the combination with a movable member constructed to carry advertising matter, of means for actuating the said member, transparent colored 115 screens arranged in front of the said member, each screen being revoluble, the axes of all the screens being parallel one to another, and means for continuously revolving the said screens in different directions. 120

5. In an advertising device, the combination with a support, of a movable band borne by the support and constructed to carry advertisements, the said support having a sight opening arranged to disclose a portion of the said band, means for actuating the said band, transparent colored screens arranged in front of the said band, each screen being revoluble, the axes of all the screens being parallel one to another, 125 130

and means for continuously revolving the said screens upon their axes.

6. In an advertising device, the combination with a support, of a movable band 5 borne by the support and constructed to carry advertisements, the said support having a sight opening arranged to disclose a portion of the said band, means for actuating the said band, transparent colored 10 screens arranged in front of the said band, each screen being revoluble, the axes of all the screens being parallel one with another, means for continuously revolving one of the said screens upon its axis, and means con- 15 structed to transmit the movement of the said revolving screen to the remaining screens to continuously revolve them.
7. In an advertising device, the combination with a movable member constructed to 20 carry advertising matter, of means for actu-
- ating the said member, transparent colored screens arranged in front of the said member, each screen being revoluble and provided with a friction wheel, the friction wheels of the said screens being arranged in 25 contact with each other, the said screens having adjustable bearings whereby the screens and friction wheels may be separated to stop the revolutions of the screens, and means for revolving one of the screens 30 continuously on its axis thereby revolving the remaining screens when the friction wheels are together.

In testimony whereof I affix my signature in presence of two witnesses.

JAMES W. PROVARD.
